United States Patent Office.

JOHN W. LYDER AND HENRY SHREVE, OF ALLIANCE, OHIO.

Letters Patent No. 79,136, dated June 23, 1868.

IMPROVED MODE OF SPLICING BELTING.

The Schedule referred to in these Letters Patent and making part of the same.

TO ALL WHOM IT MAY CONCERN:

Be it known that we, JOHN W. LYDER and HENRY SHREVE, of Alliance, in the county of Stark, and in the State of Ohio, have invented certain new useful Improvements in Mode of Splicing Belting; and do hereby declare that the following is a full, clear, and exact description thereof, reference being had to the accompanying drawings, and to the letters of reference marked thereon.

In the annexed drawings, forming part of this specification—

Figure 1 is a view of the upper side, and

Figure 3 of the bottom or under side of the fastener.

Figure 2 is a side view.

The nature of our invention consists in a four-lipped or double fastener, with or without a hinge, so constructed as to clamp the ends of the belt; these lips being screwed together, the screws passing through the belts, thereby fastening them firmly.

To enable others skilled in the art to make and use our invention, we will proceed to describe its construction and operation.

In the annexed drawings, A represents the four-winged or four-lipped fastener, provided with a hinge, C, on the lower or inner side of which are holes to admit screws *a a*, by which the belts are fastened. These screw-holes are in the ends of the lips, and between these holes are one or more posts or pins, *b b*, to pass through the belts. The object of these posts or pins is to lessen the number of screws without weakening the fastening of the belt, and thereby lessening the expense. The post or pins *b b*, passing through the belt B, fit into holes or sockets in the ridge *c*, on the upper or outside lip of the fastener A. In this ridge are also holes to admit the ends of the screws *a a* when fastening the belt. The object of the ridge *c* is to give ample room for the points of the posts and screws to accommodate a thick or thin belt, it being intended that for a thick belt the screws and posts will enter just far enough to make a secure fastening, and for a thin belt not to pass beyond the outer surface of the lip. The hinge-fastener is to be made a little shorter than the width of the belt, thereby preventing any rubbing or wearing on cone-pulleys, guides, cross-belts, &c. It can be made perfectly noiseless by putting two strips of thin leather on the under side of the fastener, and lapping over the edge of the belt and under the upper lip, which makes them perfectly secure.

If it is desired, the hinge may be dispensed with, and the fastener constructed of two pieces, one upper and one under side, and fastened in the same manner as above described.

D represents the fastener made without a hinge.

The belt-fastener may be made of brass, iron, or any other suitable material.

Having thus fully described our invention, what we claim as new, and desire to secure by Letters Patent, is—

The four-lipped metallic belt-fastener A, provided with the ridge *c* on its upper or outer side, and with or without the hinge C, arranged and operating substantially as and for the purposes herein set forth.

In testimony that we claim the foregoing, we have hereunto set our hands, this 4th day of May, 1868.

JOHN W. LYDER,
HENRY SHREVE.
